CLAIM

The ornamental design for a digital display electric soldering iron, as shown and described.

DESCRIPTION

FIG. 1 is a front, right and top perspective view of a digital display electric soldering iron, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an exploded view thereof.

The uniform broken lines depict portions of the digital display electric soldering iron that form no part of the claimed design.

The dash dot broken lines define the enlargement regions and form no part of the claimed design.
